METAL CLOSURE AND CAP FOR JARS,
BOTTLES, AND THE LIKE

Samuel Freeman, New York, N. Y.

Application February 11, 1935, Serial No. 5,891

3 Claims. (Cl. 215—46)

This invention relates to improvements in metal closures and caps for jars, bottles and the like of the type where the closure is hermetically sealed to the container through the medium of a rubber gasket or the like, and normally the cap or closure rests upon the container under pressure caused by the introduction of a vacuum into the container or otherwise.

A particular object of this invention is the provision of a novel form of cap or closure for jars, bottles and the like which can be easily released from the container to which it is attached.

Other objects of my invention will be set forth in the following description and drawing which illustrates a preferred embodiment thereof, it being understood that the above statements of the objects of my invention are intended to generally explain the same without limiting it in any manner.

In the drawing:

Fig. 1 is a plan view of a strip of material from which my improved cap is made.

Fig. 2 is a plan view showing the first operation to which the strip of material shown in Fig. 1 is subjected.

Fig. 3 is a sectional view along the line 3—3 of Fig. 2.

Fig. 4 is a side elevation of cap and jar to which it is attached.

Fig. 5 is a top plan view of Fig. 4.

Fig. 6 is an inverted plan view of the cap alone.

Fig. 7 is a sectional view partially broken away, of the top of Fig. 4 showing the cap and the method of its attachment to the container.

Fig. 8 is a sectional view, partially broken away, of the same type of cap but showing another form of container.

Fig. 9 is a front elevation of the cap alone.

Fig. 10 indicates the strip of material which is folded to produce the fold 11, and out of which is cut a blank along the line 12.

In contrast to the type of cap used at the present time, this cap although it is stamped into form from a metal blank, is formed by making separate folds, consisting of the original layer 10 and the additional layers 14 and 15 caused by the lapping of the fold 11 to secure a substantially flat surface for the entire body of the cap.

After the operation of folding, the unit is stamped to provide a finished cap with dependent sides 16 as shown in Figs. 4, 6 and 7.

It is apparent also that it is possible to produce a finished cap by first cutting a flat blank,

then folding same, and then forming the sides from the cut out blank.

It is desirable in the forming of the cap to emboss or raise the fold 11 at one point slightly, preferably near the edge of the cap to permit the insertion of a tool of some kind to distort the fold 11 when the cap is to be removed.

The reference numeral 17 indicates a rubber gasket, by which the cap is hermetically sealed under pressure to the body of the container 18.

The finished cap is indicated as 19.

In the type of cap, as at present manufactured, the cap is loosened from the container by the use of a tool operating upon the lower edge of the side 16 and it has been found in practice that the operation of loosening such caps especially in the small sizes thereof, is a difficult and cumbersome one. The principal object of my invention is to provide a cap in which the operation of loosening the cap from the container is easier than in the conventional type and in which the force necessary to remove such cap may be applied to the top of the cap itself instead of upon the side of same.

In order to remove the cap, a tool 21, shown in Fig. 5, with a sharp point on same, such as a knife-edge, or the like, is introduced at the point 20.

By lifting the tool against the lower edge of the fold 14, the entire folded portion and the cap will be distorted so as to bring the lower edge 16 of the cap away from the contiguous portion of the container so as to permit the introduction of air into the container.

When the air is once introduced the cap may be easily lifted off.

In Fig. 9 I have indicated in a dotted line how the fold, a portion of the cap, including the side thereof is bent so as to allow the introduction of air into the container.

It is apparent that it is possible to get considerably more leverage upon the fold of a cap of this type than where the force must be exerted upon the edge and side of the cap as in the present conventional form and the possibility of breaking the glass is also avoided.

I have shown a preferred embodiment of my invention, but it is clear that numerous changes and omissions may be made without departing from its spirit.

It should be noted also that the lapped or folded portion of the cap in this embodiment is part of the side and extends to the bottom of the flange.

55

Having fully described my invention, what I claim is:—

1. A closure for jars and the like comprising a metallic cap having a substantially flat top and a dependent flange engaging the sides of said jar, a gasket co-operating with the edge of said flange to form an air-tight closure, and a fold on said cap, said fold extending continuously across the top of the cap and flange.
- 10 2. A closure for jars and the like consisting of a metallic cap and a downwardly extending flange engaging the sides of said jar, means on said jar forming an air-tight closure in co-opera-

tion with said flange, the body of said cap being bent upon itself to form a continuous fold or lapped portion extending transversely of said cap and flange, said fold being adapted to receive a tool by which the cap may be disengaged from said jar.

3. A closure for jars and the like comprising a metallic cap having a dependent flange engaging the sides of the jar, said cap having a substantially flat fold extending continuously across 10 the top of the cap and flange.

SAMUEL FREEMAN.
